UNITED STATES PATENT OFFICE

162,114

ARTIFICIAL LEATHER BILLFOLD BACK
OR SIMILAR ARTICLE

Joseph Barash, Peekskill, N. Y.

Application April 1, 1950, Serial No. 8,928

Term of patent 3½ years

(Cl. D87—3)

To all whom it may concern:

Be it known that I, Joseph Barash, a citizen of the United States, residing at Peekskill, in the county of Westchester and State of New York, have invented a new, original, and ornamental Design for an Artificial Leather Billfold Back, or Similar Article, of which the following is a specification, reference being had to the accompanying drawing, forming part thereof.

The figure is a plan view of an artificial leather billfold back, or similar article, showing my new design.

I claim:

The ornamental design for an artificial leather billfold back or similar article, as shown.

JOSEPH BARASH.
